(57) **CLAIM**

The ornamental design for a cleaning brush, as shown and described.

DESCRIPTION

FIG. 1 is a front perspective view of a cleaning brush, showing my new design;

FIG. 2 is a rear perspective view thereof;

FIG. 3 is a front perspective view, shown in condition of use;

FIG. 4 is a front view thereof;

FIG. 5 is a rear view thereof;

FIG. 6 is a left side view thereof;

FIG. 7 is a right side view thereof;

FIG. 8 is an enlarged top view thereof;

FIG. 9 is an enlarged bottom view thereof;

FIG. 10 is an enlarged detail view of area 10 in FIG. 1; and,
FIG. 11 is an enlarged detail view of area 11 in FIG. 2.

The broken lines in the drawings illustrate the portions of the
cleaning brush, which form no part of the claimed design.
The dash-dot-dash broken lines depict enlarged portions that
form no part of the claimed design.
